AUTOMATIC LOCK SLIDER FOR SLIDE FASTENERS

Alexander M. Brown, Colonia, N. J., assignor to
 The North & Judd Manufacturing Company,
 New Britain, Conn., a corporation of Connecticut

Application October 19, 1945, Serial No. 623,204

7 Claims. (Cl. 24—305.14)

1

This invention relates to slide fasteners and, in particular, to the provision of new and improved lock sliders therefor.

It is an object of this invention to provide such a new and improved lock slider construction embodying new and improved automatically operating locking means utilizing a long soft lock actuating spring in such manner as to utilize the resiliency of substantially the entire length of the spring to achieve soft, easy, and convenient operation.

It is a further object of this invention to provide such a construction embodying means for confining such a lock actuating spring without impairment of its resilience by reason of the freedom afforded thereto, despite its confinement against endwise displacement.

It is a further object of this invention to provide such a slider construction which is cheap, simple, easy to assemble and extremely durable and which is capable of construction in various materials and by various known methods.

It is a further object of this invention to provide such a construction embodying a spring cover, hollow lug, or housing readily and conveniently attachable to the body of the slider, which cover, lug, or housing protects the lock actuating spring and retains or confines it in position, while also retaining the pull-tab in position wherein its trunnions are disposed between the slider body proper and the lock actuating spring.

It is a further object of this invention to provide such a slider construction embodying locking means controlled by a conventional type pull tab or pull member wherein the locking means controls or inhibits swinging of the pull tab.

These and other objects and advantages of the invention will appear from the following description taken with the accompanying drawing which forms a part thereof, and will be pointed out in the following claims.

In the drawing:

Fig. 1 is a plan view, partly cut away, of a slide fastener including, as a part thereof, an automatic lock slider embodying the principles of this invention;

Fig. 2 is an exploded, isometric view of the slider shown in Fig. 1 and illustrating the manner in which the component parts are assembled and attached;

Fig. 3 is a fragmentary section, taken substantially on the plane indicated by the line 3—3 in Fig. 1, and showing the parts in locking position;

2

Fig. 4 is a view similar to Fig. 3 but showing the parts in unlocked position;

Fig. 5 is a view similar to Fig. 3 of a modified form of slider according to this invention, with the fastener stringers omitted in the interest of clearness; and

Fig. 6 is a view similar to Fig. 5 of a second modification according to this invention.

Fig. 1 of the drawing illustrates the application of one preferred form of slider, according to this invention, to a slide fastener comprising a pair of similar stringers of which the right hand stringer is generally designated 8 and the left hand stringer is generally designated 7. Each stringer comprises a textile or other flexible tape or carrier 9 having an edge reinforcement 10 at its inner edge and a row of similar equally spaced interlocking fastener members, scoops or elements 11 secured thereto in suitable known manner as by clamping, casting, molding or by an adhesive, depending upon the material of which the interlocking members or elements are formed. Adjacent the interlocking members or scoops 11, the reinforced inner edges of the tapes are connected by a bottom stop or bottom end fitting 12 of known form. A top stop 14 of known form is attached to each reinforced inner tape edge in known manner.

Supported for sliding movement along the rows 30 of fastener members or scoops 11, to an extent limited by the bottom stop 12 and top stops 14, is a slider 15 constructed according to this invention, the slider 15 being provided with a manually engageable finger piece or pull tab 16 for convenience of operation.

The fastener is opened by manually moving the slider downwardly toward the bottom stop 12 and closed by moving the slider 15 in the reverse direction, upwardly toward the top stops 14. This closing and opening of the fastener is effected through progressive engagement and disengagement of the fastener members of scoops 11 of the stringers 7 and 8 by the cam portion of the slider 15, in a manner well known in the art.

In each form of slider shown in Figs. 3 to 6 inclusive, a "ratcheting" operation occurs when the slider is drawn upwardly on the stringers 7 and 8 to a locking position since the yielding nature of the locking spring or locking member permits the inclined lower edge surface of the locking projection to ride over the interlocking members, elements, or scoops engaged thereby during this movement. The lower, lateral, rear 55 edge surface of the locking projection, because

of its shape, obstructs accidental movement of the slider to an opening position because of its engagement with flat, or substantially flat surfaces of the fastener members, elements or scoops, as shown in Fig. 3. When, however, tension is applied to the manually engageable pull member or pull tab 16, the locking projection is moved outwardly, as shown in Fig. 4, to clear the fastener member or scoop guiding channels for the slider for free relative endwise movement between the fastener members or scoops and the slider or slider body.

While various attempts have been made, in prior constructions, to secure the advantages of a relatively long, soft spring, for actuating the locking projection, such attempts have, heretofore, failed to provide a construction, such as those herein illustrated, wherein substantially all of the length of such a spring member is utilized to actuate the locking projection, where such spring member is substantially co-extensive with the length of the slider, and where substantially the entire length thereof is unconfined, even though relative longitudinal or endwise movement between the actuating spring member and the slider body be prevented. Furthermore, such prior art lock sliders were generally of complicated construction, wherein the parts were difficult to assemble and attach together into a unitary structure.

The above disadvantages of the prior art construction are totally obviated, according to this invention, wherein the slider comprises a body of relatively simple form capable of being cast, molded or forged, one wing of which body is provided with a locking projection confining aperture or apertures receiving and guiding a locking projection or projections formed integrally with a resilient or yielding spring or actuating member of simple, cheap, form.

The trunnion portion of a pull member or pull tab is disposed between the aforesaid spring and the outer surface of the slider body, and the aforesaid locking means, including the spring and projection, are enclosed in a hollow lug or housing of simple form readily and conveniently formed and attached to the slider body for protecting the locking means both physically and functionally.

Referring to the drawing in detail, it will be seen from Fig. 2 that the slider 15 comprises a body 17 formed by a rear wing 18 and front wing 19, each wing being provided with side flanges 20, and connected at the upper end by a neck or wedge portion 20a (Figs. 3 and 4) preferably formed integrally with wings 18 and 19. The cam-like neck or wedge portion 20a forms with the wide flanges 20 a substantially Y-shaped upwardly diverging channel for guiding the fastener members, elements or scoops 11 of the stringers 7 and 8 into and out of engagement when the slider is moved upwardly or downwardly upon the stringers.

The slider front wing 19 is shown as provided with a single locking projection receiving and guiding aperture 21 disposed in suitable location for guiding the illustrated locking projection or locking prong into and out of the locking engagement with the interlocking members or scoops in the slider channel to lock and unlock the slider, as will hereinafter most clearly appear. At each end the front wing 19 is also provided with a suitable recess 22 adapted to receive end or attaching tabs on the lug or locking member housing, as will hereinafter appear.

The finger piece, pull member or pull tab 16 comprises a plate-like member provided with a suitable aperture 23 adjacent its inner end which forms the trunnion or trunnions 24. This member 16 may be formed in various ways and by various known methods, depending upon the material from which it is constructed.

The locking spring in the form shown in Figs. 2, 3 and 4 comprises an elongated looped flat spring member 25 having its forward or upper end 26 and its rear or lower end 27 extending upwardly or outwardly with a central or intermediate loop or loop portion 28 intermediate the aforesaid end portions and two oppositely disposed loops. This lock actuator spring 25 has a locking prong or locking projection 29 formed integrally therewith and bent down from one side thereof at substantially a right angle.

The locking projection or locking prong 29 has a straight forward edge surface 30, a similar rear edge surface 31, and an inclined inner end or end edge surface 32. The forward and rear edge surfaces 30 and 31 are closely engaged and guided by the end surfaces of the aperture or slot 21 for prevention of relative endwise movement of the projection or prong 29 with respect to the slider body. The aperture or slot 21 also guides this locking prong or projection 29 against transverse movement with respect to the slider by closely engaging the flat side surfaces thereof, thus confining the movement of the locking prong or projection 29 to linear movement inwardly and outwardly of the slider for projection into, and withdrawal of the inner end thereof from, the fastener member or scoop guiding channel of the slider.

This confinement of the movement of the locking prong to the aforesaid linear movement, and against transverse or longitudinal movement with respect to the slider, is accomplished entirely without confinement of the spring proper 25 intermediate its end portions 26 and 27.

Support of these end portions 26 and 27 is accomplished by the end walls of the lug or spring housing which is generally designated 33. In the form shown in Figs. 2, 3 and 4, this lug or housing 33 is a hollow box-like structure provided with an elongated, substantially rectangular, outer or front wall 34, similar and obverse side walls 35, and downwardly or inwardly extending upper end wall 36 and lower end wall 37. The side walls 35 are both provided with similar trunnion guiding apertures or openings 38 through which the trunnion 24 of the pull member or tab 16 extends, beneath the intermediate loop portion 28 of the spring member 25, as shown in Fig. 3.

The end walls 36 and 37 of the lug or housing 33 are preferably of such length and width as to be capable of having their end portions 36a and 37a bent over into the aforementioned recesses 22 in the front wing 19 of the slider body, as shown Fig. 3, in such manner as to provide a flush structure.

While the spring 25 has been illustrated as provided with a single locking prong or projection 29 engaging the scoops of a single stringer, these members 29 may be multiplied and offset to engage the scoops of both stringers simultaneously in a manner well known in the art.

In assembling the parts of the slider shown in Figs. 2, 3 and 4, the forward and rear end portions 26 and 27 of the spring member 25 are pushed upwardly into the interior of the lug 33, whereupon they closely engage the inner surface of the front wall 34 thereof, whereupon the trunnion 24 of

the pull member or tab 16 is engaged in the inner portion of the intermediate loop 28 of the spring member 25, which loop registers with the apertures or openings 38 in the side walls 35. The lug is then pressed home whereupon the end portions of the end walls 36 and 37 will be disposed in and adjacent the above-described recesses 22 in the front wing 19 of the slider body. The extreme end portions 36a and 37a of the end walls 36 and 37 are then bent toward one another, substantially at a right angle from the end walls 36 and 37 into the recesses 22, to form a flush structure, as shown in Fig. 3.

As will readily appear from Fig. 3, the lock actuator or spring 25 normally yieldingly urges or biases the locking prong or projection 29 toward locking position wherein it is interlockingly engaged between adjacent interlocking members or scoops of the left hand stringer 8. The trunnion 24 of the pull member 16 is then retained between the intermediate loop portion 28 of the spring 25 and the outer surface of the front wing 19 of the slider body.

The looseness of this retentive connection depends upon the arc of the intermediate loop portion 28, which may be varied to provide for any desired degree of free swinging movement of the pull member or tab 16. Most preferably, the arc of the loop portion 28 is predeterminedly designed to exert a braking action upon the trunnion 24 in order that objectionable free swinging or dangling of the pull member or tab 16 is prevented when the parts are in the locking position as shown in Fig. 3. If desired the trunnion 24 may be made non-circular or may be roughened to enhance or increase this "braking" action.

This is an extremely meritorious feature since such free swinging and dangling of the pull tab is extremely undesirable, for instance, where slide fasteners are attached to sleeves of garments.

Unlocking of the slider may be accomplished by applying tension to the pull member or tab 16 in the appropriate direction, i. e. downwardly, of the fastener for opening the fastener or upwardly thereof to close the fastener.

Such applications of tension cause the trunnion 24 to cooperate with the under surface or inner surface of the loop portion 28 (which forms a cam or cam surface) to cause the locking prong or projection 29 to be lifted or drawn outwardly from engagement with the fastener members or scoops 11 as shown in Fig. 4, against the yielding force exerted thereon by the spring proper 25.

The embodiment illustrated in Fig. 5 is generally similar to the above described embodiment of Figs. 2, 3 and 4, but the slider body, locking member (spring and projection) and lug or housing have been somewhat modified. In this embodiment of Fig. 5, the sidewalls 35 are omitted from the lug or housing 33a and slots or apertures 36b and 37b have been provided in the end walls thereof for a purpose which will hereinafter appear.

The loops have been omitted from the lock actuating spring 25a, which thus becomes of gently arcuate form, and bosses or "bumps" 25b are formed therein adjacent but inside each end wall 36 and 37 after assembly of the spring 25a to the lug or housing 33a. These projections or bosses 25b protect the slider against escape of the extreme end portions of the spring 25a from their retaining slots 36b and 37b in which they are supported, substantially without impairment of the resiliency or freedom of the spring 25a.

Since elimination of the loops from the spring

25a eliminated the cam or cam surface provided by the inner surface of the intermediate loop 28 of the spring, the function of this omitted cam is supplied by the longitudinal upstanding lug 5 19b formed on the front wing 29 and provided with a centrally disposed transversely extending cam notch or surface 19c receiving and supporting the trunnion 24 of the pull member of tab 16 beneath the spring 25.

10 In the embodiment of Fig. 6, the slider body is similar to that of the embodiment of Figs. 2, 3 and 4. The spring 25c is flat except for the single loop 28a (generally similar both physically and functionally with the intermediate loop 28 of spring or actuator). The lug or housing 33b is similar to the lug or housing 33 except that the top or outer wall 34b is inclined or rounded at its end portions, and the end walls 36 and 37 eliminated except for the end portions 15 36b and 37b thereof, the sidewalls 28b being modified accordingly, and the trunnion retaining apertures or openings 38b therein are substantially rectangular. The sidewalls of these apertures exert no cam action or cam effect upon the 20 trunnion 24 of the pull member or pull tab 16.

The method of assembling the pull members or pull tabs, hollow lugs or spring housings, locking means, and slider bodies of the embodiments of Figs. 5 and 6 is similar to that of the 25 embodiment of Figs. 2, 3 and 4 described above and will be readily apparent to those skilled in the art from Figs. 5 and 6 when taken with the description of the assembly of the parts of the aforesaid embodiment of Figs. 2, 3 and 4.

30 35 From the above description it will clearly appear that I have provided a new and improved auto-lock slider for slider fasteners accomplishing, in addition to the above enumerated advantages, other objects and advantages apparent 40 from the above description and the following claims.

It is, of course, to be understood that the above description is merely illustrative, and in nowise limiting, and that I desire to comprehend within 45 my invention such modifications as are included within the scope of the following claims.

Having thus fully described my invention, what I claim as new and desire to secure by Letters Patent is:

50 1. In a slide fastener slider of the class described, a body having therein a fastener member guiding channel, said body being provided with an aperture extending from one side thereof into said channel, locking means comprising a resilient 55 yielding flat-type spring member free of attachment to said body and having a locking projection intermediate its ends, said projection being confined in said aperture for movement into and out of said fastener member guiding channel, 60 locking spring confining means on said body overlying said aperture and engaging both end portions of said resilient yielding spring member for restraining said end portions against end-wise movement in either direction with respect 65 to said body, and a pull member having a trunnion extending transversely of said body between said flat spring locking member and said body and directly engageable with both.

70 2. In a slide fastener slider of the class described, a body having therein a scoop guiding channel, said body being provided with an aperture extending from one side thereof into said channel, locking means comprising a resilient substantially flat yielding spring member of substantial length free of attachment to said body

75

and having a locking projection intermediate its ends extending substantially vertically from its general extent and confined in said aperture for movement into and out of said scoop guiding channel only, locking spring confining means on said body overlying said aperture and engaging at least one end portion of said spring member for restraining it against endwise movement, said spring member normally biasing said locking projection toward movement-blocking engagement with scoops in said scoop guiding channel, and a manually engageable member having a portion extending between said locking member and said body and directly engageable with both, whereby tension applied to said manually engageable member will withdraw said locking projection from engagement with said scoops to unlock said slider.

3. In a slide fastener slider of the class described, a body having therein a scoop guiding channel and having an aperture extending from the front side thereof into said channel, locking means comprising an elongated substantially flat lock actuating leaf spring free of attachment to said body and having a locking prong intermediate its ends and confined in said aperture for movement into and out of said scoop guiding channel only, and means on said body overlying said aperture and engaging the end portions only of said lock actuating spring for restraining its end portions against endwise movement in either direction, said locking member confining means having openings accommodating the trunnion portion of a pull member, and a pull member having a trunnion extending through said openings and being disposed between said locking member and said body.

4. In a slide fastener slider of the class described, a body having therein an upwardly divergent longitudinal scoop guiding channel with a locking projection guiding opening extending from the front thereof into said channel, locking means comprising a longitudinally disposed leaf spring free of attachment to said body and substantially coextensive with said body and having an integral locking prong intermediate its ends, said locking prong being confined in said aperture for movement into and out of said scoop guiding channel only and being normally biased inwardly by said spring toward locking position, and a hollow lug on the front side of said body overlying said locking projection guiding opening and engaging both end portions only of said resilient yielding spring member for controlling the movement of said end portions, and lock controlling means comprising a pull tab having a trunnion disposed between said spring and the front of said body and directly engageable there-

with, said hollow lug having openings in its side walls accommodating said trunnion for rotation and translation, said openings protecting said spring against permanent set by limiting the movement of said trunnion.

5. The structure defined in claim 4, wherein said leaf spring is provided with two spaced inwardly extending loops engaging the front of said body and an intermediate connecting outwardly extending loop accommodating said trunnion, and wherein the ends of said spring are disposed closely adjacent the outer wall of said hollow lug.

15 6. The structure defined in claim 4, wherein said leaf spring is provided with an intermediate upwardly directed loop adjacent said locking prong yieldingly retaining said trunnion clamping between said spring and the front of said body, said loop providing a cam surface translating longitudinal translation of said trunnion into outward lifting force applied through said spring to said locking prong for unlocking said slider.

7. In a slide fastener slider of the class described, a body having therein a fastener member guiding channel, said body being provided with an aperture extending from one side thereof into said channel, locking means comprising a resilient substantially flat elongated spring member free of attachment to said body and having a locking projection intermediate its ends, said projection being confined in said aperture for linear movement only into and out of said fastener member guiding channel, a pull tab for controlling said locking means including a trunnion secured between said spring member and said body and directly engageable with both and a protective housing secured to said body and overlying said locking means, said housing engaging the end portions only of said spring member, limiting endwise movement of said spring member, controlling movement of said trunnion and protecting said locking means from damage by crushing.
